UNITED STATES PATENT OFFICE.

CHARLES H. BUHMAN, OF MAYWOOD, AND WILLIAM C. BUHMAN AND ERNEST E. IVERSEN, OF CHICAGO, ILLINOIS.

DIE-STOCK OILER.

1,150,660.

Specification of Letters Patent. Patented Aug. 17, 1915.

Application filed May 4, 1914. Serial No. 836,236.

To all whom it may concern:

Be it known that we, (1) CHARLES H. BUHMAN, (2) WILLIAM C. BUHMAN, and (3) ERNEST E. IVERSEN, citizens of the 5 United States, residing at (1) Maywood and (2 and 3) Chicago, respectively, in the county of Cook and State of Illinois, have invented certain new and useful Improvements in Die-Stock Oilers, of which the following is a specification.

This invention relates to new and useful improvements in die stocks and more particularly to means for oiling a die which consists of hollow die stock oilers constituting reservoirs for oil and a novel valve for each handle which may be readily controlled by the operator to regulate the oil feed.

An object of importance is to provide means for conveniently and easily oiling 20 stocks that may be readily attached to various styles of die stocks without necessitating any material change in the construction thereof.

Another object is to provide a novel valve 25 for each handle to control the oil feed and which is operable by a push button at the end of each handle and automatically closes upon release of pressure upon the push button.

Another important object is to provide a 30 die stock oiler of the character described that is simple as to construction, reliable and efficient in operation and inexpensive to manufacture.

These and other objects may be attained 35 by the structure illustrated in the accompanying drawings in which,

Figure 1 is a top plan view of a die stock showing our improved oiling means attached, Fig. 2 is a longitudinal sectional view showing the device in assembled position, Fig. 3 is a transverse sectional view taken on line 3—3 of Fig. 2, Fig. 4 is a detail perspective view of the die block, Fig. 5 is a 40 detail sectional view of the valve casing, and Fig. 6 is a detail view of the valve.

Referring to the drawings forming a part 45 of this specification and in which like numerals designate corresponding parts, the numeral 1 designates the body of a die stock having a die block receiving opening 2 of any suitable character formed therein. On each side of the body is formed an internally threaded socket 3. The sockets 3 receive the 50 externally threaded ends of hollow handles

4 which act as reservoirs as will be later more fully described. Openings 5 extend from the inner ends of the sockets through the body 1 and communicate with the die block receiving opening 2. Feed tubes 6 are 60 mounted within the openings 5 and communicate at their ends with the hollow handle 4 and die receiving opening 2 respectively. The inner ends of the tubes 6 project into the die opening 2 and rest within 65 grooves 7 formed on opposite sides of the opening in a die block 8.

The die block 8 is clamped in the usual manner in the die receiving opening 2 of the die stock and is oiled in a reliable and efficient manner by the tubes 6 which at their 70 inner ends rest as described within the grooves 7. The grooves 7 convey the oil to the cutting face of the die and act as a guide for the oil.

Mounted within the inner ends of the hollow handles 4 are cylindrical valve casings 13 provided intermediate their ends with conical valve seats 14 and having the openings therein enlarged to one side of the 80 valve seat to provide pockets 15. The inner ends of the valve casings 13 are slightly enlarged and internally screw threaded as at 16 to receive plugs 17 that are removably mounted within the portions 16 and have 85 central apertures in which are mounted the outer ends of the tubes 6. The casings 13 serve to seal the inner ends of the hollow handles 4. Mounted within each of the 90 valve casings 13 is a slid valve 18 that is provided with a frusto conical end face 19 and longitudinal spaced peripheral grooves 20 communicating with the face 19. The frusto conical face 19 of each valve is 95 designed to coöperate with the valve seat 14 in each casing. The valve 18 is provided at its inner end with a circular recess 21 and at the other end with an internally screw threaded opening 22. The inner end of the 100 valve stem 23 is turned within the screw threaded opening 22 of each of the valves 18 while the other end of each valve rod is disposed adjacent the outer end of each handle interiorly thereof. Mounted on the 105 outer ends of the hollow handles 4 are cylindrical sleeves 24 that are internally threaded on one end and provided at their other ends with inwardly extending annular flanges 25. These flanges 25 are designed to 110 rest upon the outer ends of the handles 4.

A push button 26 is mounted within each of the sleeves 24 and provided with an annular flange 27 at its inner end. The flanges 27 engage the inner edges of the flanges 25 and the inner surface of the handles 4. The outer faces of the push buttons 26 are disposed normally flush with the outer faces of the sleeves 24.

Each of the push buttons is provided at its inner end with an inwardly extending recess 28 in which is mounted the outer end of each valve rod 23. The outer ends of the valve rods 23 are spaced from the push buttons so as to allow the push buttons to be moved inwardly a slight distance prior to their engagement with the ends of the valve rods, so that an accidental inward movement of the push button 26 would not unseat the valves 18. A collar 29 is formed adjacent the outer end of each valve rod 23 and engages one end of a helical expansive spring 30. The helical expansive springs 30 are mounted within the recesses 28 and serve to hold the push buttons normally spaced from the outer ends of the valve rods. Mounted within the recesses 21 in the valves 18 are expansive springs 31 that are similar to the ones 30 and at their outer ends engage the plugs 17. The springs 31 serve to hold the valves 18 normally in closed position.

In operation the handles 4 are filled with oil preferably by removing the cylindrical sleeves 24 and push buttons co-operating therewith. When it is desired to oil the die 35 the operator forces the push buttons 26 inwardly until they engage the outer ends of the valve rods 23 and move the valves out of registration with the seats. The oil is allowed to flow in the casings through the 40 outer open ends through the grooves 29 in the valves 18 into the pockets 15 in the casings and from thence through the tubes 6 to the grooves 7 in the die block. By operating both handles the die will be oiled in an efficient manner upon opposite sides 45 thereof. Upon the removal of the pressure from the push buttons the springs 31 serve to automatically force the valves into closed position. The spacing of the ends of the 50 valve rods from the push buttons insures a

reliable valve closing action as friction is eliminated. The push buttons are held normally in inoperative position by the springs 30.

With reference to the foregoing description and accompanying drawings it will be readily seen that there has been provided simple and inexpensive means to easily and reliably lubricate die stock that may be easily operated when the operator is using 60 the die.

In practice, it has been found that the form of this invention, illustrated in the drawings and referred to in the above description, as the preferred embodiment, is 65 the most efficient and practical; yet realizing that the conditions concurrent with the adoption of this device will necessarily vary, it is desired to emphasize the fact that various minor changes in details of construction, proportion and arrangement of parts may be resorted to, when required, without sacrificing any of the advantages of this invention, as set forth in the claim.

What is claimed is:—

The combination with a die stock having a hollow handle constituting an oil reservoir, a push button slidably mounted within the outer end of the handle and having a recess opening out through the inner side 80 thereof, a valve casing secured within the inner end of the handle, a valve mounted in the casing, a spring normally retaining the valve seated, a rod secured at its inner end to the valve and having its outer end 85 disposed in the recess in spaced relation to the end wall thereof, a collar on the rod in spaced relation to the inner side of the push button, and a spring mounted on the rod between and engaging the collar and the end 90 wall of said recess.

In testimony whereof we affix our signatures in presence of two witnesses.

CHARLES H. BUHmann.
